UNITED STATES PATENT OFFICE.

JAMES W. A. MCKILLICAN, OF MONTREAL, QUEBEC, CANADA.

TOBACCO PIPE.

1,410,586.

Specification of Letters Patent. Patented Mar. 28, 1922.

Application filed September 2, 1919. Serial No. 321,169.

To all whom it may concern:

Be it known that I, JAMES W. A. MCKILLICAN, a subject of the King of Great Britain, and resident of the city of Montreal, in the Province of Quebec and Dominion of Canada, have invented certain new and useful Improvements in Tobacco Pipes, of which the following is a full, clear, and exact description.

10 This invention relates to improvements in tobacco pipes, and the object of the invention is to provide a pipe which may be manufactured at very small additional cost and which will give a dry, cool smoke.

A further object is to provide a pipe which will absolutely prevent the entrance of saliva into the pipe bowl.

The device consists of a pipe of substantially ordinary shape, having between the 20 stem proper and bowl an upwardly projecting barrier which will effectually prevent the entrance of moisture from the stem into the bowl. This barrier further serves to provide an elongated smoke passage in which 25 the smoke cools with a consequent condensation of its tarry constituents.

In the drawings which illustrate the invention:

Fig. 1 is a vertical longitudinal section of 30 the pipe.

Fig. 2 is a section on the line 2—2, Figure 1.

Fig. 3 is an elevation of another type of moisture dam.

Fig. 4 is a sectional view illustrating a 35 dam chamber constructed separately from the pipe.

Referring more particularly to the drawings, 11 designates the bowl, 12 the stem and 13 the mouth-piece of a pipe, the mouth-piece 40 being fitted to the stem in any well known manner. A bore 14 extends through the mouth-piece and stem into the bottom of the bowl. A second bore 15 is provided in the bowl approximately parallel with the axis 45 thereof and intersecting the bore 14. This bore 15 may be open at either the bottom or the top end or at both. A portion of the length of the bore 14 may be enlarged as at 16, such enlargement extending from 50 the bore 15 a suitable distance into the mouth-piece. A barrier or dam 17 is inserted in the bore 15 and is located transversely of the pipe, as clearly shown in Figure 2, so that it separates that portion of 55 the bore adjacent the bowl from the remainder of the bore. In Figure 1, the construc-

tion is shown in its simplest form with the bore 15 open at the bottom and the dam inserted from the bottom and held by means of a screw or push plug 18. In the construction shown, the upper end of the bore 15 is closed by a plug 19, which may be removed to facilitate cleaning of the bore 15. Obviously, the end of the bore 15 may be permanently closed. The upper end of the 60 dam 17 does not extend quite to the closed end of the bore, so that smoke from the bowl may flow up one side of the dam, over the top of the same, and down the other side into the main portion of the bore 14. This 65 dam, which fits tightly in the bore 15, is preferably a simple, cylindrical member 70 grooved on opposite sides. The grooves may be straight, as shown in Figures 1 and 2, or may be helical as shown in Figure 3. 75 When it is desired to insert the dam from the top of the bowl, the plug 19 will be replaced by the plug 18 carrying the dam. In such a case, the plugs must be screwed in until the dam seats on the plug at the bottom of the bore and a hole 20, shown in Figure 3, provided through the dam adjacent its carrying plug 18 to enable the smoke 80 to get from one groove to the other. In order to delay the passage of smoke through 85 the stem and mouth-piece, a double worm 21, which fits tightly in the enlarged portion 16 of the bore, may be provided, so that the smoke passing through the grooves of the worm will have ample opportunity to cool 90 and the tarry constituents thereof will condense in the grooves of the worm, so that they will not reach the smoker's mouth. The double worm which divides the smoke 95 will hasten this cooling. Obviously, the worm 21 may be omitted.

The operation of the pipe is extremely simple. The smoke flows in the manner previously described. When it is desired to clean the pipe, the dam 17, plug 19 and 100 worm 21 are removed, the latter by first removing the mouth-piece which carries the worm. Pipe cleaners may now be passed from end to end through the bores 14 and 15. If the dam or worm or both should be 105 lost or broken, the usefulness of the pipe is not destroyed as it may be smoked in the usual way as long as the ends of the bore 15 are closed.

The bore 15 or dam chamber may be 110 formed separately from the pipe, as shown in Figure 4, and screwed into the upper sur-

face of the stem, the dam being screwed in from the lower surface as before so as to block the bore of the stem and divert smoke up into the attached dam chamber.

5 Having thus described my invention, what I claim is;—

1. In a tobacco pipe, the combination with a bowl, stem and mouth-piece, of a chamber extending upwardly from the stem bore, and 10 a dam in the stem extending upwardly within said chamber having helically disposed smoke passages on opposite sides thereof; and a communication passage between the helical smoke passages of said dam 15 near the top of the chamber, said passages connecting the bowl with the bore of the stem and mouth-piece.
2. In a tobacco pipe, the combination with

a bowl, stem and mouth-piece, of a dam located between the bowl and mouth-piece 20 arranged to stop passage of liquid between the bowl and mouth-piece and to increase the length of smoke passage, and a double helically grooved member inserted in the mouth-piece forming a duplex smoke passage of elongated form.

3. In combination with a device according to claim 1, a double helically grooved member inserted in the mouth-piece forming a duplex smoke passage and co-operating with 25 the helically grooved dam in increasing the length of smoke passage between the bowl and mouth-piece.

In witness whereof, I have hereunto set my hand.

JAMES W. A. McKILLICAN.
